UNITED STATES PATENT OFFICE.

JOHN W. TEMPLIN, OF MARION, INDIANA.

STEAM-PUMP.

SPECIFICATION forming part of Letters Patent No. 548,480, dated October 22, 1895.

Application filed February 26, 1895, Serial No. 539,823. (No model.)

To all whom it may concern:

Be it known that I, JOHN W. TEMPLIN, of Marion, in the county of Grant and State of Indiana, have invented new and useful Improvements in Steam-Pumps; and I do hereby declare the following to be a full, clear, and exact description of said invention, reference being had to the accompanying drawings, and to the letters of reference marked thereon, which form a part of this specification.

My invention relates to steam-pumps or steam pumping-engines, and has particular reference to the valve mechanism thereof.

In the form of steam-pumps most commonly employed the pistons of the steam and water cylinders are connected to a single rod, which carries tappets adapted to strike a lever or levers, which through certain slide-rods or other connections operate the valves of the steam-cylinder.

The object of the present invention is the production of a simple and durable valve mechanism for the steam-cylinder of this type of engine, and in which the initial movement of the valve in either direction shall be imparted by the steam-piston itself, while the completion of the movement initiated by the piston shall be quickly caused by the steam after it has done its work in the main steam-cylinder.

To these ends the invention consists in the construction and combination of parts substantially as hereinafter described and claimed.

In the drawings, Figure 1 is a vertical longitudinal section of the steam-cylinder of a pumping-engine and of my improved valve mechanism secured to the top thereof, the valve itself being shown in side elevation. Fig. 2 is a section on line 2 2 of Fig. 1. Fig. 3 is a detail elevation of the valve from the side opposite that shown in Fig. 1. Fig. 4 is a plan and partial diagram to illustrate the ports of the valve-seat, this view giving substantially the same illustrations that it would if it were a horizontal section on line 4 4 of Fig. 1, omitting the valve. Fig. 5 is a diagram illustrating the ports of the cylindrical valve. Fig. 6 is a detail sectional view on line 6 6 of Fig. 1.

The two Figs. 4 and 5, if cut out of cardboard, would serve to illustrate the cut-off action of the valve on its seat.

Parts which appear in several figures of the

drawings are indicated by similar reference- 55 letters in said figures.

A indicates the steam-cylinder of a steam pumping-engine, a the piston-rod thereof, and a' the piston, all these parts being of the ordinary or any preferred construction. 60

B indicates the valve-chest, which is internally cylindrical and has a flat under side, as indicated at b, Fig. 2, to fit a similarly-flattened portion of the steam-cylinder A, to which it is bolted. The valve-chest has a live-steam 65 inlet i and an exhaust-outlet e, and contains the cylindrical valve C, which is free to slide longitudinally in the said chest, each end of the valve having a suitable packing-ring, as indicated at c, in order that the valve may be 70 moved by the force of steam between the ends of the chest and the valve, as hereinafter described.

Near each end of the valve-seat is a cross-shaped opening, the arms of which form ports 75 i⁴ e⁶ for steam, as presently described, while the central elongated part or slot b' is to permit the passage of the arm or tappet d, one of which is secured to the under side of the valve near each end thereof by a screw d', 80 passing through the valve and into the base of the tappet. These two tappets might be integral with the valve, so far as the operation is concerned, but for convenience in assembling the parts they are detachable, as 85 just described. In order that the said screws may be accessible, suitable holes are made in the upper side of the valve chest or casing and closed by screw-plugs d², as indicated in Fig. 1. No steam passes through the slots b', 90 even if the bases of the tappets do not closely fit the slots, for the reason that said slots are at all times covered by the lower central part of the valve, the ports being entirely aside from the slots b', which are in the line of reciprocation of the arms or tappets, as will be readily understood by a comparison of Figs. 4 and 5. Therefore all the steam is confined 95 in passing to the ports formed in the valve itself and none can escape through the said 100 slots. Between each slot b' and the end of the valve-seat is a shallow depression or steam-port f, and a similar but larger depression or port g is formed at one side of the port f on what may be termed the "ex- 105

The valve C is cored out to form an upper

steam-chamber i' and a lower steam-chamber i^2 , which two chambers are permanently connected by the passage i^3 , and being always supplied with live steam balance each other. 5 The chamber i^2 , as the valve reciprocates, communicates alternately with the two ports i^4 i^4 of the valve-seat and supplies live steam to the steam-cylinder to operate the pump. The valve is also cored out nearly its entire 10 length on the other side of its lower central portion, as at e' , and this coring communicates with the exterior of the valve at e^2 e^3 e^4 e^5 , forming ports for the exhaust-steam. The ports e^6 in the valve-seat form exhaust-ports 15 from the steam-cylinder, and as the valve reciprocates the two ports e^6 communicate alternately with the ports e^2 e^5 , so that the exhaust-steam may find its outlet through the coring e' and through the ports e^3 or e^4 to the 20 outlet e .

At each extreme end of the valve-chest is a slight enlargement h , and a small port h' leads diagonally from the live-steam chamber i' through each end of the valve to the under 25 side thereof close to its end, as indicated in Fig. 1.

The supply of steam to the cylinder and the exhaust therefrom as the valve reciprocates being evident from the foregoing description, taken in connection with the drawings, I will now describe the operation of the valve, the initial movement of which is imparted by the contact of the piston with the tappets d d alternately, as will also be readily 35 understood.

The piston having moved to the left, as in Fig. 1, to an extent so as to partially move the valve in the same direction, the steam in the cylinder A passes through the port f at 40 the right and acts against that end of the valve to complete its movement, while the exhaust at the left-hand end of the valve is taking place through the port g at that end and the port e^2 of the valve. At the moment 45 when the lower end of the port h' clears the valve-seat so as to admit live steam to the enlargement h steam passes into said enlargement, so as to cushion the movement of the valve. During this operation of the 50 valve the ports for the admission of live steam to the cylinder A and the exhaust therefrom have been shifted, and the piston moves its full stroke to the right and initiates the reverse movement of the valve by coming 55 in contact with the tappet d , when the same operation as above stated will be repeated, but in the opposite direction.

The cylindrical valve, as shown, has a tendency to constantly preserve a perfect fit on 60 its seat, for the reason that as wear occurs the weight of the valve and the pressure of the steam on it will keep it in smooth contact with the seat; and since all the ports except the main inlet at i are below the horizontal 65 plane of the center of the valve and seat there can be a great deal of wear before the valve will permit any leakage.

Having thus described my invention, what I claim is—

1. A steam pump comprising in its construction a steam cylinder and a closed valve seat therefor, a single valve fitted to said seat, said valve having suitable inlet and outlet ports, and having arms or tappets extending into the path of movement of the piston in the cylinder, the ports in the valve and seat being entirely aside from the line of reciprocation of the tappets. 70

2. A steam pump comprising in its construction a steam cylinder and a closed valve chest 80 therefor, a single balanced valve fitted to said chest and having packed ends and having steam inlet and outlet ports therethrough, arms or tappets extending from the valve into the path of movement of the piston in the cylinder, steam ports from the cylinder to the valve chest beyond the ends of the valve, and exhaust ports from the ends of the valve chest through the valve, the ports in the valve and chest being entirely aside from the line 85 of reciprocation of the tappets. 90

3. A steam pump comprising in its construction a steam cylinder and a closed valve chest therefor, a single valve fitted to said chest and having suitable inlet and outlet ports, 95 rigid arms or tappets extending from the valve into the path of movement of the piston in the cylinder, said chest having an enlargement at each end, and the valve having a small live steam port leading to said enlargement. 100

4. The combination with the slotted valve chest having ports i^4 e^6 , of the cylindrical valve C having the elongated steam chamber i^2 and the coring e' having openings or ports e^2 , e^3 , e^4 , e^5 , and the arms or tappets d d secured to the valve and extending through the slots of the valve chest. 105

5. The combination with the valve chest having the slots b' , the ports e , i^4 e^6 , and the shallow ports f g , of the valve C having the connected chambers i' i^2 and the coring e' having ports e^2 e^3 e^4 e^5 . 110

6. The combination with the valve chest having the enlargement h and the ports e i^4 e^6 f and g , of the valve C having the connected chambers i' i^2 , the coring e' having the ports e^2 e^3 e^4 e^5 , and the ports h' . 115

7. A steam pump comprising in its construction a steam cylinder and a closed cylindrical valve chest therefor, a single cylindrical valve fitted to said chest and having suitable inlet and outlet ports below the horizontal plane of its center, and arms or tappets extending from the valve into the path of movement of the piston in the steam cylinder, the ports in the chest and valve being entirely aside from the line of reciprocation of the tappets. 120

In testimony whereof I affix my signature in presence of two subscribing witnesses.

JOHN W. TEMPLIN.
